UNITED STATES PATENT OFFICE.

EDWARD B. WESTON, OF DAYTON, OHIO.

COMBINED WRAPPING-PAPER HOLDER AND PRINTER.

SPECIFICATION forming part of Letters Patent No. 406,318, dated July 2, 1889.

Application filed July 2, 1888. Serial No. 278,765. (No model.)

To all whom it may concern:

Be it known that I, EDWARD B. WESTON, a citizen of the United States, residing at Dayton, in the county of Montgomery and State 5 of Ohio, have invented certain new and useful Improvements in Combined Wrapping-Paper Holders and Printers, of which the following is a full, clear, and exact description, reference being had to the accompanying drawings, 10 forming part of this specification.

My invention relates to that class of wrapping-paper holders now in general use in stores, in which the paper is in a continuous roll and is drawn and torn therefrom, as required for use, in sheets of proper size; and it has for its object the improvement in the construction of this class of devices.

The novelty of my invention will be here-with set forth, and specifically pointed out 20 in the claims.

In the accompanying drawings, Figure 1, Sheet 1, is a front elevation of a paper-roll holder removed from its case and embodying my invention. Fig. 2, Sheet 1, is a side elevation of the same. Fig. 3, Sheet 1, is an enlarged sectional detail of the pitman. Fig. 4, Sheet 1, is an enlarged end elevation of the printing-roller. Fig. 5, Sheet 2, is a rear elevation of Fig. 1. Fig. 6, Sheet 2, is a sectional 30 side elevation of the machine within its case and taken from the opposite side of Fig. 2.

The same letters are used to indicate identical parts in all the figures.

A A are two uprights between which the 35 usual paper-roll B is removably journaled in the slots a. Also journaled between the uprights A, above the roll B, are two rollers C and D in frictional contact, the former of which C, I designate the "bed-roller," and 40 which is covered with felt, rubber, or other elastic material, and the latter D in this instance formed in three sections to secure lightness and likewise covered with felt, rubber, or other elastic material and which I designate the "printing-roller." In this instance the 45 roller D is composed of three metal drums secured by spoked hubs, as seen in Fig. 4, upon a shaft E, forming the axis of the roller. The central portion is the longest and has secured to it a type-plate F, of either rubber, metal, or wood, and with a convex face coincident with the surface of the roller. The pa-

per from the roll B is passed up behind and between the rollers C and D, and their frictional contact is such that upon drawing forward the paper revolution is imparted to the rollers. If desired, the journals of both or either of the rollers may be adjustable to regulate the frictional contact, as will be readily understood by those skilled in the art. 55

In Figs. 1 and 2 I have shown the spindles of the roller C extended through vertical slots j in the uprights A, and resting in pillow-blocks k, carried loosely upon the upper end of set-screws l, bearing in lugs m projecting from the uprights. By means of these screws the frictional contact between the rollers may be adjusted as desired. 60

Secured centrally upon a transverse bar G, supported by the uprights A, in rear of the 70 roller B, is a vertical post H, having a socket at its upper end, in which is pivoted an inking-disk I, having a clutch-ratchet b upon its under side. J is a shaft journaled in the uprights A, about half-way between the bar G 75 and the printing-roller, and provided with two bell-crank arms c, one on each side of the disk I, and carrying in their upper slotted ends an inking-roller K, of the usual or any suitable construction, which rests upon the 80 disk I, as shown.

Secured upon one end of the shaft E is a disk L or a crank-arm, which is connected by a spring or yielding pitman M to a crank-arm N upon the adjacent end of the shaft J. 85 One form of pitman (shown in Fig. 3) consists of two telescoped parts united by a spiral spring d. The parts are so adjusted that upon the revolution of the printing-roller by the act of drawing out the paper causes the 90 shaft J to be oscillated forward, so as to bring the inking-roller in contact with the type-plate at its forward edge, and the spring in the pitman by yielding maintains the contact of the inking-roller with the type-plate 95 until the rear edge of the latter has just passed, whereupon the shaft J is oscillated backward and the inking-roller is returned upon the disk I. In this way the inking-roller only comes in contact with the type-plate, so as to ink the same at each complete 100 revolution of the roller D, as will be readily understood.

To give the disk I intermittent revolution,

as is customary in printing-machines, I employ an arm O, Figs. 5 and 6, which is pivoted to a stud e, projecting from the post H, and which carries at its upper end a pivoted dog 5 f, engaging with the ratchet b. The lower end of the arm O is connected by a spring g to the bar G. P is a wiper-arm extending from the shaft J, and so adjusted that when the shaft J is oscillated backward, upon the 10 return of the inking-roller, it presses upon the lower end of the arm O and throws its dog f forward to effect a fresh engagement with the ratchet b, and as soon as the shaft J is oscillated forward and the inking- 15 roller leaves its disk I the spring g resets the arm O and causes its dog f to partially turn the disk I, as will be readily understood.

To prevent the roller B from unwinding too rapidly, any suitable brake mechanism may 20 be applied to it. For instance, I have shown a spring h secured to one of the uprights A and bearing against the end of the shaft of the roller B, thereby creating a friction upon said shaft to constitute a brake.

25 Of course it will be understood that the roller D may be solid or continuous, if desired, and the width of the type-plate may be varied at will; and, again, the shaft J, instead of being actuated from the roller D, may be 30 actuated from the roller C.

From the above it will be seen that I provide a simple automatic printing mechanism, which is applied to a paper-roll, and which is actuated entirely by drawing forward the paper 35 per as it is desired for use, thus enabling store-keepers to print their cards or other matter upon their wrapping-paper without trouble and at a slight expense. I have also provided for the machine thus described a 40 case or cabinet Q, Fig. 6, in two hinged parts, and with an opening in front for the passage of the paper, said opening being provided with a cutting-edge i, against which the paper is torn off for use after it has been printed.

Having thus fully described my invention, 45 I claim—

1. The combination, with the supports for a wrapping-paper roll and a bed-roller and printing-roller in frictional contact and between which the paper from the first-mentioned roll is passed, of an inking-plate and an inking-roller, with connecting mechanism between said printing-roller and inking-roller, whereby the drawing forward of the paper actuates the bed, printing, and inking rollers 55 to cause the printing of the paper, substantially as described.

2. The combination, with the supports for a wrapping-paper roll and a bed-roller and printing-roller in frictional contact and between which the paper from the first-mentioned roll is passed, of a pivoted inking-plate with connecting mechanism between said plate and printing-roller, and an inking-roller with connecting mechanism between 60 said inking-roller and printing-roller, whereby the drawing forward of the paper actuates the inking-plate and the bed, printing, and inking rollers to cause the paper to be printed, substantially as described.

3. The combination and arrangement of the supports A, bed-roller C, printing-roller D, carrying a type-plate F, said rollers C and D being in frictional contact and having the paper from the roll B passed between them, 75 the shaft J, connected to the roller D by a yielding pitman M, and provided with the arms c, carrying the inking-roller K, and the inking-plate I, provided with the ratchet b, and actuated by the arm O, carrying the dog f, the spring g, and the wiper-arm P, substantially in the manner and for the purpose specified.

EDWARD B. WESTON.
